MULTIPLE ELECTRODE RADIOTRON

Application filed May 20, 1924, Serial No. 714,542. Renewed August 1, 1930.

This invention pertains to systems for the amplification of energies and more specifically to electronic methods of amplification and apparatus therefor.

It is an object of the invention to provide an electron-emitting apparatus superior to constructions now in use.

It is another object of the invention to provide apparatus of the character specified that may be used for both radio-frequency and audio-frequency amplification in a suitable system.

It is a further object to combine in a single vacuum tube device, a plurality of arrangements or apparatus for performing a plurality of functions heretofore requiring separate devices.

It is a still further object of the invention to eliminate the difficulties arising from difference in degree of vacuum as between several thermionic devices as heretofore employed in one system.

Yet further objects are to provide a device such as a radio tube that will be simple and cheap of construction, efficient and reliable of operation, that may have substantially twice the life of any tube now in use and one that will have certain novelties of construction and function that have not heretofore been obtained and as will more particularly appear from the description and claims and from the drawings in which;

Fig. 1 is a side elevation of one form of electrode mount including the stem flare constructed in accordance with our invention;

Fig. 2 is a top plan view taken along the line II—II of Fig. 1;

Fig. 3 is a view similar to that of Fig. 1 of a different form embraced by our invention;

Fig. 4 is another view similar to Fig. 1 of a still further form of our invention; and,

Fig. 5 is a view of Fig. 4 taken along the line V—V of Fig. 4.

In an application filed by Siegmund Loewe, August 26, 1921, Serial No. 495,777, entitled Multiple boosters or multiple vibration generators and assigned to the Westinghouse Electric & Manufacturing Company, a multiple electrode electronic device is described

and claimed, and while a tube constructed in accordance with the teaching of said application is most desirable and has excellent qualities, many difficulties may be encountered in its construction. By our invention, we overcome those difficulties and provide an economical and efficient device.

It will be readily appreciated that in order to obtain the minimum plate resistance or the minimum space charge effect, it is essential in radio tube construction to have the average distance from plate to filament as small as possible and to provide a filament of great length. It will also be evident that if for mechanical reasons the plate-filament distance cannot be less than a certain value, the first condition will be entirely fulfilled by a cylindrical plate and that if the filament cannot be greater than a certain length, the use of two or more filaments or cathodes is advantageous. Such a construction would make it possible to use a length of filament greater than could be supported in a single strand without the addition of center or other supports and at the same time a length of filament that will permit the use of those voltages and currents for a temperature at which suitable electron emission and long life are obtained.

Referring to the drawings, a stem 2 carrying leads 4, 6, 8, 10, 12 and 14 through press 16 together with the electrodes hereinafter described, constitutes the mount of one form of my invention. The leads 4, 6, 8, 10, 12 and 14 may constitute the supports for the electrodes in addition to performing their function as leads, although they may be connected as shown in the figure to electrode supporting and conducting members in any suitable manner. The lead 10 is connected to a supporting member 18 which passes up through the center of a neck 20, connecting together, two cylindrical portions 22 and 24 of a plate electrode or anode, and serves to support said plates. This neck portion 20 may be integral with the plates as shown or may be formed in any other suitable manner. Preferably positioned within the cylindrical portion constituting the anodes are the grids or space current controlling electrodes

26 and 28, which are mounted upon separate and unitary supports 30 and 32 respectively, which may extend the whole length of the grid. The third electrode element of the tube 5 comprises the filaments or cathodes 34 and 36, which extend through the centers of the grids between a support formed by portion 38 at right angles to a supporting lead 40, and individual supporting leads 42 and 44 10 to which they are respectively secured, the supporting leads being sealed into the press 16. The plates and grids are arranged concentrically about the filaments as will be noted in Fig. 2. In this construction, the leads 15 4, 8 and 12 serve the two filaments 34 and 36 and by appropriate connections the two filaments may be operated in parallel, in series, or individually as may be desired. The construction shown in Fig. 3 does not 20 differ materially from that shown in Fig. 1 except that the filaments are supported by a horizontal support 46 which is attached to the plate support 18' by means of a glass or other insulating bead 48. In this construction 25 the filaments may be burned only in series but in both the construction of Fig. 1 and that of Fig. 3, the two grids may be used independently as, for instance, in cases where one grid is used for controlling radio-frequency 30 amplification and the other for controlling audio-frequency amplification.

The construction shown in Fig. 4 can be best understood by reference to Fig. 5 in which it will be noted that a support 18", in 35 this case supports the two grids by passing through a mid web portion 19 thereof while the double barrelled plate or anode 22-24 is supported by means of supports 50 and 52. Various other modifications may be 40 made but for the sake of convenience we have illustrated only three.

With the constructions described, i. e., with the electrodes concentric and substantially surrounding one another, it has been found 45 practical to obtain a plate resistance as low as 8,000 ohms as compared to a plate resistance of 10,000 ohms with the common form of rectangular plate-filament distance, the same value of amplification constant being 50 obtained in the two cases. It therefore follows as a corollary and actually works out in practice, that this construction makes it possible to obtain a higher amplification constant with the same value of plate resistance. 55 Tubes made in accordance with the invention and used in a radio system give greater amplification and less distortion.

Various modifications of the construction 60 may be made without departing from the spirit of the invention or the terms of the claims hereinafter appended.

What is claimed is:

1. In a vacuum tube, a compound anode 65 of sheet material comprising a plurality of hollow cylindrical portions and a double-

wall connecting portion of less diameter than said cylindrical portions.

2. In a vacuum tube, a compound anode of sheet material comprising a plurality of cylindrical portions, a double-wall connecting portion and a supporting member enclosed by the walls of said connecting portion. 70

3. In a thermionic tube, a compound electrode of sheet metal comprising a plurality of cylindrical portions interconnected by a 75 double-wall web portion extending substantially parallel to the axes of said cylindrical portions, and a supporting element affixed to said double-wall portion.

4. In a thermionic tube, a compound electrode of sheet metal comprising a plurality of cylindrical portions interconnected by a 80 double-wall web portion extending substantially parallel to the axes of said cylindrical portions, a part of said double-wall portion 85 being modified to accommodate a supporting element, and a supporting element affixed to said modified part.

5. In a thermionic device, a compound electrode of sheet metal comprising a plurality of cylindrical portions interconnected by a 90 web portion integral therewith, said web portion being channeled to receive a supporting element, and a supporting element disposed within said channel. 95

6. In a vacuum tube, a cathode, a compound anode of sheet material comprising a plurality of hollow cylindrical portions and a double-wall constricted connecting portion.

7. In a vacuum tube, a cathode a compound anode of sheet material comprising a plurality of hollow cylindrical portions and a double-wall constricted connecting portion, and a substantially cylindrical grid in each 100 of said cylindrical portions. 105

8. In a vacuum tube, a cathode, a compound anode of sheet material comprising a plurality of hollow cylindrical portions and a double-wall constricted connecting portion, and a substantially cylindrical grid in each of 110 said cylindrical portions, said cylindrical grids being connected by a double-wall connecting portion.

9. In a vacuum tube, a cathode, a compound anode of sheet material comprising a plurality of hollow cylindrical portions and a double-wall constricted connecting portion, and a substantially cylindrical grid in each of 115 said cylindrical portions, said cylindrical grids being connected by a double-wall connecting portion, and a support for said grids attached to said last mentioned double-wall connecting portion. 120

10. A vacuum tube containing a plurality of substantially cylindrical anode portions, substantially cylindrical grid portions inside of said anode portions, and cathode portions inside of said grid portions, said anode portions having a double-wall connecting por- 125 130

tion, said grid portions having double-wall connecting portions.

11. A vacuum tube containing a plurality of substantially cylindrical anode portions, substantially cylindrical grid portions inside of said anode portions, and cathode portions inside of said grid portions, said anode portions having a double-wall connecting portion, said grid portions having double-wall connection portions, said anodes being connected to each other.

12. In a vacuum tube, a compound grid comprising a plurality of hollow cylindrical portions and a double-wall connecting portion of less diameter than said cylindrical portions.

13. In a vacuum tube, a compound grid structure comprising a plurality of cylindrical portions, a double-wall connecting portion and a supporting member enclosed by the walls of said connecting portion.

In testimony whereof, we have hereunto subscribed our names, this 8th day of May, 1924, and this 13th day of May, 1924.
